UNITED STATES PATENT OFFICE

127,578

DESIGN FOR A VELOCIPED OR THE LIKE

Cecil C. Cash, Glen Ellyn, Ill., assignor to Montgomery Ward & Co., Incorporated, Chicago, Ill., a corporation of Illinois

Application March 19, 1941, Serial No. 93,796

Term of patent 14 years

To all whom it may concern:

Be it known that I, Cecil C. Cash, a citizen of the United States, residing at Glen Ellyn, in the county of Du Page and State of Illinois, have invented a new, original, and ornamental design for a Velocipede or the Like, of which the following is a specification, reference being had to the accompanying drawings, forming a part thereof.

In the drawings—

ing my new design, the characteristic features of which reside in the portions shown in solid lines;

I claim:

The ornamental design for a velocipede or the like, substantially as shown and described.

CECIL C. CASH.
